DENTURE BRUSH

Lloyd Miller, 2531 NE, 43rd St.,
Lighthouse Point, Fla. 33064

Filed Jan. 5, 1968, Ser. No. 10,063

Term of patent 14 years

Int. Cl. D4—02

U.S. Cl. D4—28

FIG. 1

FIG. 2

FIG. 3

FIGURE 1 is a front elevational view of a denture brush showing my new design;

FIGURE 2 is a side elevational view of the denture brush; and

FIGURE 3 is a back elevational view of the denture brush.

Design features of the denture brush as shown in the drawings are the offset and parallel relationship of the handle and the bristle-holding portions of the brush, the slant of the connecting portion between the handle and bristle-holding portions with indentations at and adjacent the base of the slanting portion, the curvature of the bristle-holding portion, and the raised and circular na-

ture of the boss where the smaller group of bristles is received.

I claim:

The ornamental design for a denture brush, as shown and described,
